United States Patent Office

Des. 193,456
Patented Aug. 21, 1962

193,456

PENCIL HOLDER

Menno Bellar, 21 Rockland St., Fitchburg, Mass.

Filed Jan. 30, 1961, Ser. No. 63,755

Term of patent 3½ years

(Cl. D74—1)

FIG. 3

FIG. 4

FIG. 1 is a front elevational view of a pencil holder showing my new design;

FIG. 2 is an edge view looking in the direction of arrow 2 in FIG. 1;

FIG. 3 is a bottom plan view, looking in the direction of arrow 3 in FIG. 1; and

FIG. 4 is a section on line 4—4 of FIG. 1.

The upper forwardly projecting ledge has five circular openings therein that are aligned with the pencil receiving cups in the lower ledge.

I claim:

The ornamental design for a pencil holder, as shown and described.
